US0D1094437S

(12) **United States Design Patent** (10) **Patent No.:** **US D1,094,437 S**
Bay et al. (45) **Date of Patent:** **** Sep. 23, 2025**

(54) **DISPLAY SCREEN OR PORTION THEREOF WITH GRAPHICAL USER INTERFACE**

(71) Applicant: **Workstorm.com LLC**, Chicago, IL (US)

(72) Inventors: **Jeffery Bay**, Austin, TX (US); **Anatoliy Yudovich**, Riverwoods, IL (US); **Nicholas Stech**, Chicago, IL (US); **Adrian Miller**, Oroville, CA (US); **Raj Fernando**, Chicago, IL (US)

(73) Assignee: **Workstorm.com LLC**, Chicago, IL (US)

(**) Term: **15 Years**

(21) Appl. No.: **29/878,651**

(22) Filed: **Jun. 26, 2023**

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet

Related U.S. Application Data

continuation of application No. 15/914,319, filed on Mar. 7, 2018, now Pat. No. 10,915,866.
